UNITED STATES PATENT OFFICE.

CUNNINGHAM N. McLAUGHLIN, OF WINONA, MINNESOTA, ASSIGNOR TO NEW WINONA MANUFACTURING COMPANY, OF WINONA, MINNESOTA, A CORPORATION OF MINNESOTA.

DESIGN FOR A GRINDING-MILL STANDARD.

No. 39,627.

Specification for Design.

Patented Oct. 20, 1908.

Application filed July 6, 1908. Serial No. 442,259. Term of patent 14 years.

To all whom it may concern:

Be it known that I, CUNNINGHAM N. McLAUGHLIN, a citizen of the United States, residing at Winona, in the county of Winona and State of Minnesota, have invented a new, original, and ornamental Design for a Grinding-Mill Standard, of which the following is a specification, reference being had to the accompanying drawing, forming part thereof.

The figure is a perspective view of a grinding mill standard showing my new design.

The salient features of the design thus

shown comprise the base from which rises a pair of standards with laterally extending arms at the top thereof upon which are supported the pair of arches having openings through their body portion.

I claim:

The ornamental design for a grinding mill standard, as shown and described.

CUNNINGHAM N. McLAUGHLIN.
